UNITED STATES PATENT OFFICE.

JAMES E. WEST, OF WASHINGTON, DISTRICT OF COLUMBIA.

DESIGN FOR A BADGE.

41,532.

Specification for Design.

Patented July 4, 1911.

Application filed February 15, 1911. Serial No. 608,857. Term of patent 3½ years.

To all whom it may concern:

Be it known that I, JAMES E. WEST, a citizen of the United States, residing at Washington, in the District of Columbia, have invented a new, original, and ornamental Design for a Badge, of which the following is a specification, reference being had to the accompanying drawing, forming a part thereof.

The figure of the drawing is a plan view of a badge showing my new design.

The leading feature of my design consists in the representation of a fleur de lis with a scroll beneath the same, the upwardly and laterally extending ends of the scroll joining the

lower minor lateral branches of the fleur de lis. The main side arms or branches of the fleur de lis bear each a star and centrally of the fleur de lis is an eagle whose claws rest on the apices formed by the bottom of the fleur de lis while his wings lie in the lateral extension or branches close to the stars. On his breast the eagle bears a shield.

I claim:

The ornamental design for a badge, as shown.

JAMES E. WEST.

Witnesses:

GUSTAVE HERTZSCHUCH,
JAMES M. SPEAR.
